CLAIM

The ornamental design for a teething ring, as shown and described.

DESCRIPTION

FIG. 1 is a top, front, right side perspective view of a teething ring, showing our new design;

FIG. 2 is a front elevational view thereof;

FIG. 3 is a rear elevational view thereof;

FIG. 4 is a left side elevational view thereof, the right side elevational view thereof being a mirror image;

FIG. 5 is a top plan view thereof; and,

FIG. 6 is a bottom plan view thereof.

The broken lines depict portions of the teething ring that form no part of the claimed design.
